Barnwell R. King

UNITED STATES PATENT OFFICE

BARNWELL R. KING, OF KALAMAZOO, MICHIGAN

SHIELD FOR IGNITION COILS

Application filed May 25, 1931. Serial No. 539,978.

The object of the invention is to provide a shield for the ignition coils of automobiles and the like which is economical to manufacture, simple in construction and efficient in 5 operation.

Objects relating to details and economies of my invention will appear from the description to follow. The invention is defined and pointed out in the claims.

10 A structure which is a preferred embodiment of my invention is illustrated in the accompanying drawing, in which:

Fig. 1 is a fragmentary view in side elevation of the shield applied to an ignition coil 15 container.

Fig. 2 is a top plan view of the metal clip.

Fig. 3 is a side elevation of Fig. 2, and

Fig. 4 is a fragmentary view in vertical section showing how the metal clip is embedded in the rubber skirt.

Referring to the drawing, numeral 1 indicates the dashboard of a modern conventional automobile to which is attached an ignition coil container 2 by means of brackets 3. An 25 insulated conductor 4 connects the terminal of the ignition coil within the container 2 to the distributor of the automobile, not shown. A rubber nipple 5 embraces the connection between the conductor 4 and the terminal of 30 the ignition coil within the container 2.

During severe rain storms, the radiator of the vehicle permits a fine mist to be blown by the fan back onto the container 2, the nipple 5 and the conductor 4. When the surface 35 of these elements becomes saturated, a short-circuited path is formed thereon for the high frequency distributor currents which causes the engine of the vehicle to miss and/or knock. This may also be caused by a leaky 40 radiator. To obviate this, I provide a shield 6 which preferably comprises a metal clip 7 having perforations 8 which is embedded in the upper rim of a rubber skirt 9. The 45 rubber extends through the perforations or slots 8 thereby forming an interlock between the clip and the skirt. The rubber is preferably vulcanized around the clip 7, as shown by Fig. 4, so that the clip forms a resilient reinforcing member for the skirt.

50 In operation, the shield is slipped over

the container 2 so as to depend below the bottom of the container to protect the upper part of the conductor 4, the nipple 5 and the bottom of the container from the watery mist mentioned above. The connection between 55 the skirt and the container is preferably a close fit so that the water is prevented from running down the side of the container under the shield.

While I have illustrated and described a 60 preferred modification of the invention, it will be understood that various changes may be made therein, for example, the metal clip 7 may be of any desired material and shape and the skirt may be made of any desired material, without departing from the spirit of the invention which is to be limited only by the prior art and the scope of the following 65 claims.

Having thus described my invention, what 70 I claim as new and desire to secure by Letters Patent, is:

1. In a device of the class described, a resilient perforated metal clip and a skirt of rubber embedding said clip, the rubber being vulcanized to the clip. 75

2. In a device of the class described, a clip of resilient material and a skirt of rubber embedding said clip, the rubber being vulcanized 80 to the clip.

3. In a device of the class described, a perforated clip of resilient material and a skirt of rubber-like material embedding said clip and vulcanized thereto. 85

4. In a device of the class described, the combination with a resilient metal supporting member, in the form of a split ring, of a rubber skirt embedding, vulcanized on and depending therefrom. 90

5. In a device of the class described, the combination with a split ring spring clip, of a water-proof and non-conducting shield integrally united therewith. 95

6. In a shield for ignition coil casings, the combination with an insulating water-proof skirt and resilient means in the form of a split ring integrally united with said skirt for attaching it to a casing. 100

7. In a shield for ignition coil casings, the combination with an insulating water-proof

skirt and means in the form of a split ring integrally united with said skirt for attaching it to a casing.

8. An ignition coil shield comprising a resilient split ring of metal, and a split skirt of rubber vulcanized thereon, the ring being disposed near one end of the skirt.

9. An ignition coil shield comprising a resilient split ring, and a split skirt of rubber vulcanized thereon.

10. In witness whereof I have hereunto set my hand.

BARNWELL R. KING.
